UNITED STATES PATENT OFFICE.

FREDERICK TRANSOM, OF WASHINGTON, DISTRICT OF COLUMBIA, ASSIGNOR TO COOPER HEWITT ELECTRIC COMPANY, OF HOBOKEN, NEW JERSEY, A CORPORATION OF NEW JERSEY.

SYSTEM OF RECTIFICATION.

Application filed April 2, 1925. Serial No. 20,180.

My invention relates to apparatus for converting alternating currents of electricity into direct, or continuous direction currents. More particularly the invention utilizes the properties of what is known in the art as a hot cathode rectifier tube, as improved, described and claimed in an application for United States Letters Patent, Serial No. 578,181, filed July 28, 1922, by Earl H. Rollinson.

One object of my invention is to increase both the life run and load capacity of such tubes without undue heating.

Another object is to equalize temperature strains on the electrode seals. Other objects and advantages will appear as the invention is described in connection with the accompanying drawings, which form a part of this specification, and in which:—

20 The single figure shows diagrammatically a system of connections used in my invention.

In the drawing 1 represents a rectifier tube, as modified by the improvements of 25 the Rollinson application, above referred to, one feature of which is that the tube dispenses with a heating filament entirely. This tube is shown connected into a single wave, single phase rectifier circuit, but the 30 improvements here disclosed may readily be applied to circuits for the rectification of both waves of an alternating current, either single phase, or any of the several well known polyphase circuits, by those 35 skilled in the art.

The source of supply shown is a transformer T, provided with two sections, 10 and 11. Section 10 is the load section and 40 11 is a small load capacity portion used solely for excitation of the primary of a high tension, high frequency coil H. C. Starting at terminal 16, a wave in the right direction to pass through tube 1 will traverse reactance coil R. C. battery B, switch 45 8, anode 5 and through tube 1 to terminal 9 of the transformer. The tube 1 contains a gas of the argon group at low pressure and is made one way conductive by an initial excitation, or ionization, set up by a 50 high tension, high frequency current which is derived from coil H. C., as shown in the diagram, but any other high frequency

source of current operating at a suitable potential may be substituted equally well for the means shown.

55 This initial ionization is accomplished by closing switch 6 on contact 13, which impresses a high tension, high frequency current from the secondary of coil H. C. across the electrodes 3, 4. Under these conditions 60 when load switch 8 is closed a current will start in the tube, flowing from anode 5 to one of the electrodes 3 or 4, depending on how the tube is connected into its socket to complete a circuit to terminal 9 of transformer section 10. After this load current is once started switch 6 may be opened and the tube will continue self exciting on load current alone running from anode 5 to electrode 3, as a cathode.

70 Up to this point the conditions of operation of the system are the same as that described in Rollinson application Serial No. 578,181, referred to above. It will be noted, however, that the tube when thus used leaves 75 electrode 4 standing dead, whereas it has just as much current carrying capacity as electrode 3. In order to utilize the full current carrying capacity of the tube and its two electrodes, 3 and 4, as joint cathodes 80 for anode 5 I have provided an additional contact point 12 on which the switch 6 may be placed after the period of initial ionization has been accomplished, and the tube is working on a single electrode, 3 for 85 instance. The effect of placing switch 6 on contact 12 will be to provide an additional path for the space current from anode 5 through electrode 4, now acting as a cathode, to the terminal 9 of transformer section 10. 90 In this position switch 6 acts as an equalizer across leads 3 and 4.

It will thus be seen that the improvements disclosed not only allows twice the current 95 through the tube with the same seals, but the additional current flow through electrode 4 has a temperature equalization effect on the base of the tube which tends to more uniform rectification and longer life of the tube.

100 I have shown at 7 a reversing switch which may be used, if desired, to change the direction of exciting current flow. It is well known that the tension and current

waves of an induction coil, such as can be used at H. C. are dissymmetrical at the make and break, and the switch 7 may be used to select the wave train developing the best 5 excitation characteristics. Switches 15 are used to control the relative amounts of current taken up by each of the electrodes 3 and 4 by setting these switches 15 to put in a small amount of resistance 14 in series 10 with one or the other of those electrodes. Such a control conduces to an equal wear of both electrodes, and to this end also the socket should permit occasional changes in the electrode which is initially ionized.

15 While I have shown only two electrodes 3 and 4 as adapted to be converted into joint cathodes, it is obvious that a greater number of electrodes could be joined up one after the other to take space current in parallel.

20 It will be noted that when the tube is working on load current it is completely insulated from its exciting coil by an open circuit at contact 13 and that the load and exciting circuits are always separated by a 25 gap at G. The condenser K may be connected by switch 17 across the leads 3 and 4

to steady the operation of the tube in both the starting and running positions.

What I claim as my invention is—

1. In a rectification circuit, a space tube 30 provided with a load anode, a cathode, an exciting anode, and means for converting the exciting anode to a load cathode.

2. A rectification system, comprising a rectifying circuit and a starting circuit and 35 means for interconnecting said circuits including an electrode which is in the starting circuit exclusively during the starting period, and subsequent thereto in the work 40 circuit.

3. A rectifier system comprising a thermionic tube provided with a re-entrant stem, an anode and a cathode element, the latter comprising spaced conductors mounted on said stem, and means whereby said conductors may be used to effect either an initial 45 ionization of the tube, or may be used jointly as a cathode element.

Signed at Washington, D. C. this 23 day of March A. D. 1925.

FREDERICK TRANSOM.
